(57) **CLAIM**

The ornamental design for a food cutter handle, as shown and described.

DESCRIPTION

FIG. 1 is a perspective view of the food cutter handle. FIG. 2 is a side view of the food cutter handle shown in FIG. 1.

FIG. 3 is another side view of the food cutter handle shown in FIG. 1. FIG. 4 is front view of the food cutter handle of FIG. 1. FIG. 5 is a rear view of the food cutter handle of FIG. 1. FIG. 6 is a top view of the food cutter handle of FIG. 1; and, FIG. 7 is bottom view of the food cutter handle of FIG. 1.

The present application is directed to the design illustrated in the drawings. The broken line portions of the disclosure are for illustrative purposes only and form no part of the claimed design.
